HOWARD J. KERR, OF WESTFIELD, NEW JERSEY, ASSIGNOR TO THE BABCOCK & WILCOX COMPANY, OF BAYONNE, NEW JERSEY, A CORPORATION OF NEW JERSEY

STEAM BOILER AND SUPERHEATER

Application filed February 7, 1929. Serial No. 338,111.

My invention is particularly useful in connection with a steam boiler having spaced banks of inclined water tubes with a superheater located between the two banks, though it will be understood that my invention is not limited to this position of the superheater.

My invention will best be understood by reference to the accompanying drawings, in which I have illustrated certain embodiments thereof, and in which Fig. 1 is a vertical sectional view taken along the line 1—1 of Fig. 3 through a steam boiler and superheater embodying one form of my invention; Fig. 2 is a front view of the boiler taken along the line 2—2 of Fig. 1; Fig. 3 is a sectional plan view taken along the line 3—3 of Fig. 1; Fig. 4 is a fragmentary vertical sectional view illustrating a superheater embodying a modified form of my invention; Fig. 5 is a sectional elevation taken on the line 5—5 of Fig. 4; Fig. 6 is a sectional elevation taken on the line 6—6 of Fig. 4, and Fig. 7 is a sectional elevation taken on the line 7—7 of Fig. 4.

Like reference characters indicate like parts throughout the drawings.

Referring now to the drawings, 10 is a steam and water drum for a steam boiler comprising upper and lower spaced banks of water tubes 11 and 12, certain of the tubes in the middle portion of each bank being omitted in the drawings. The tubes of the two banks are connected at one end to the down-take headers indicated generally at 13, and comprising an upper nest of headers 131 to which the tubes of the bank 11 are connected at one end and a lower nest 132 to which the tubes of the lower bank 12 are connected at one end. The headers 131 and 132 are connected together by nipples 14, and the upper ends of the headers 131 are connected to the steam and water drum by nipples 15.

Similarly, the opposite ends of the tubes 11 and 12 are connected to headers indicated generally at 16, the tubes of the bank 11 being connected to upper headers 161, and the tubes of the lower bank 12 being connected to lower headers 162, the two sets of headers being connected together by tubes 17, and

the upper headers 161 being connected to the steam and water drum by return tubes 18. Preferably, two adjacent nipples, which connect the upper and lower nests of headers, are bent away from each other as at 141 (see Fig. 2). In the embodiment illustrated, the nipples so bent are located at the downtake end of the boiler.

Steam is supplied to the superheater, which is indicated generally at 19, through a plurality of steam outlet pipes 20 which are connected at one end to the steam and water drum, and spaced therealong preferably at the top center line thereof, as best shown in Fig. 1. In the embodiment illustrated, the tubes 20 are arranged in a plurality of groups, here shown as four in number, which supply steam to a corresponding number of sections of the superheater. The steam outlet pipes 20 pass downwardly alongside of the drum, pass through the front casing immediately beneath the drum as illustrated in Fig. 1, and then pass downwardly in front of the headers 13 and between the headers and the front casing. The outlet pipes 20 are preferably provided with removable flanged sections 21 opposite the upper bank of tubes to permit the withdrawal or cleaning of the boiler tubes in the upper bank or deck from the downtake end of the boiler when necessary. The steam supply tubes are located far enough away from the downtake headers to permit the removal of the handhole plates thereof (not illustrated).

The steam outlet pipes 20 are bent at their lower ends, as at 22, the pipes of a given group preferably being bent into the same vertical plane as illustrated in Fig. 2, and the bent portions extending between the bent nipples 141 into the space between the upper and lower banks of tubes, the bent ends of the tubes preferably being parallel, as at 23, as illustrated in Fig. 1.

The end of each of the pipes 23 is connected to a branched fitting 24, as best shown in Fig. 3, and a plurality of superheater tubes 25, here illustrated as four in number, are connected to each branch as by expanding and welding their ends into openings in the fitting. The superheater tubes are preferably

U-shaped in form, as best shown in Fig. 3, and each section preferably comprises a plurality of loops. The opposite ends of the superheater tubes are connected to other fittings 26 which are, in turn, connected by curved tubes 27 to similar fittings at the left thereof, and one end of the next group of U-shaped tubes of a given section are connected thereto. The extreme ends of the tubes of a given section are preferably connected to a fitting 241 which is the same as or similar to the fitting 24, and these fittings are, in turn, connected by tubes 242 to a header or headers 28. In the embodiment of my invention illustrated, one header is illustrated at the left-hand end of the boiler as viewed in Fig. 3, and a similar header, not illustrated, would be located at the right-hand end thereof. In the embodiment illustrated, one of the headers 28 serves two sections of the superheater, while the header at the other end of the boiler would serve the other two sections thereof. The outlet of the header is indicated at 29.

In the embodiment of my invention illustrated in Figs. 1 and 2, the end of the superheater adjacent to the fittings 24 is supported by suspension members 30, preferably in the form of rods, which are clamped or otherwise secured to the lower row of tubes of the upper bank as at 31, though it will, of course, be understood that it could be supported by a plate or plates surrounding the boiler tubes 11 of the upper bank. The rods or bars 30 preferably extend between the superheater tubes 25 to the lower side of the superheater, and may be secured to a bar 32 as shown, on which in turn is supported a baffle 33 which may be made up of a plurality of plates (see Fig. 3) provided with openings the walls surrounding which engage the ends of the superheater tubes adjacent to the fittings 24.

A baffle 34 extends upwardly across the tubes of the upper bank 11, a plate or fitting 35 being interposed between the lower end of this baffle and the plate 33 which extends across the superheater tubes and forming a seal therebetween. This baffle comprises a flame plate 341 fitted around the tubes of the upper bank, and tiles 342 are supported by said plate. The ends of the superheater tubes adjacent to the fittings are thus supported by all of the tubes of the upper bank through the suspension members 30 to the tubes of the lower row of the upper bank, and through the flame plate 341 to the remaining tubes thereof.

The combustion chamber is illustrated at 36 beneath the lower bank of tubes which are preferably exposed for substantially their entire length to the radiant heat of the furnace. An inclined baffle 37 extends from the upper end of a furnace wall 38, the said baffle being laid upon the upper row of tubes of the lower bank 12.

An inclined baffle member 39 extends from the free end of the baffle 37 upwardly to the cross plate 33. A baffle 40 extends downwardly from the roof across the tubes of the upper bank, so that the gases flow upwardly across the tubes of the lower bank, then across the superheater tubes and over the first pass of the tubes of the upper bank, then downwardly over the second pass of the upper bank and upwardly to an outlet flue. 75

The outlet headers 28 are preferably anchored to the upper row of tubes of the lower bank 12, as at 41, and the straight pipes 23 are preferably anchored against the nipples 14 by suitable clamping or other members, as at 42. The free ends of the U-tubes of the superheater are supported by a pier 43 which extends across and is supported by the upper row of tubes 12 of the lower bank. This pier preferably comprises a plate 431 having a flange to which is secured a plate 432 extending downwardly across and surrounding some of the tubes 12 of the lower bank. One end of the superheater tubes, therefore, is supported from the boiler tubes of the upper bank, while the opposite end thereof is supported from boiler tubes of the lower bank. Longitudinal movement of the superheater is prevented by the anchoring members 41 and 42. The sections can be replaced by disconnecting the tube and branch fittings, raising them above the other sections and passing them out through a door in the side wall (not illustrated). 90

In the embodiment of my invention illustrated in Figs. 1 to 3, no common steam inlet header for the superheater is provided, an equal distribution of the steam from the steam and water drum to the various tubes of the superheater being provided by means of the branched fittings. While I have illustrated each fitting as comprising a single branch, it will, of course, be understood that these branches could themselves be subdivided in order further to subdivide the flow of steam before reaching the superheater tubes, the steam flowing in series parallel relation to the various branches. Furthermore, while I have shown outlet headers for the superheated steam, it will be understood that the superheated steam could be led to a common main by means of fittings of the same or similar character as those by which steam is led to the superheater, it only being necessary to multiply the number of such fittings connected in series parallel relation. All of the superheater tubes are preferably of the same diameter, as illustrated. 115

In the embodiment of my invention illustrated in Figs. 4 to 7, the steam boiler may be of the same general character as that illustrated in Figs. 1 to 3, the same comprising upper and lower banks of tubes 11 and 12 which are shown in only a fragmentary manner, and which are connected to downtake 125

- and uptake headers which may, in turn, be connected to a steam and water drum in the same manner as illustrated in Figs. 1 to 3. Instead of conducting the steam from the steam and water drum by outlet steam pipes directly to the branched fittings to which the superheater tubes are connected, as in Figs. 1 to 3, the outlet steam pipes from the steam and water drum (not illustrated) are connected to the inlet superheater header 44 to which are connected short pipes 441 which are, in turn, connected to fittings 26^a which may be the same as or similar to those illustrated in Figs. 1 to 3.
- 5 To each of the fittings 26^a are connected a plurality of superheater tubes 25^a having reverse bends, as at 45, to form loops 46, the tubes being spaced by spacing plates 25^b. Both the loops 46 and the straight portions of 10 the tubes extending from the fittings are preferably substantially parallel to the boiler tubes and to each other as illustrated. The other ends of the superheater tubes are similarly connected to outlet fittings 261^a which 15 are, in turn, connected by pipes 47 to the outlet header 28^a. Both the inlet header 44 and the outlet header 28 are preferably supported on saddles 48 which are, in turn, supported on tubes 12 of the lower bank.
- 20 In the embodiment illustrated in Fig. 4, both ends of the superheater tubes are preferably suspended from the tubes of the upper bank by suspension members 49 and 50 which 25 may be arranged in a manner similar to the suspension members shown in Fig. 1.
- 25 I claim:
1. In combination, a steam boiler comprising a steam and water drum, two spaced banks of water tubes connected at one end to 30 compartments connected by nipples, two adjacent nipples being bent away from each other, a plurality of outlet steam pipes connected to the steam space of said steam and water drum and extending between said bent 35 nipples into the space between said banks of tubes, fittings to which said pipes are connected, and superheater tubes located between said banks of boiler tubes and connected at one end to said fittings.
  - 40 2. In combination, a steam boiler comprising a steam and water drum, two spaced banks of inclined water tubes connected at their ends to vertically spaced nests of down-take and uptake headers connected by nipples, two adjacent nipples at one end of the boiler being bent away from each other, a plurality of outlet steam pipes connected to the steam space of said steam and water drum and extending downwardly therefrom, said pipes being bent at different levels into the same vertical plane and extending between said bent nipples, fittings to which said pipes are connected, and superheater tubes located between said banks of boiler tubes and connected at one end to said fittings, headers with which the other ends of said superheater tubes communicate, said outlet steam pipes being anchored against said nipples and said headers being anchored to said lower bank of boiler tubes.
  - 45 3. In combination, a steam boiler comprising a steam and water drum, two spaced banks of inclined water tubes connected at their ends to vertically spaced nests of down-take and uptake headers connected by nipples, two adjacent nipples at one end of the boiler being bent away from each other, a plurality of outlet steam pipes connected to the steam space of said steam and water drum and extending downwardly therefrom, said pipes being bent at different levels into the same vertical plane and extending between said bent nipples, fittings to which said pipes are connected, and superheater tubes located between said banks of boiler tubes and connected at one end to said fittings.
  - 50 4. In combination, a steam boiler comprising a steam and water drum, two spaced banks of inclined water tubes connected at their ends to vertically spaced nests of down-take and uptake headers connected by nipples, two adjacent nipples at one end of the boiler being bent away from each other, a plurality of outlet steam pipes connected to the steam space of said steam and water drum and extending downwardly therefrom, said pipes being bent at different levels into the same vertical plane and extending between said bent nipples, fittings to which said pipes are connected, and superheater tubes located between said banks of boiler tubes and connected at one end to said fittings.
  - 55 5. In combination, a steam boiler comprising a steam and water drum, two spaced banks of inclined water tubes connected at their ends to vertically spaced nests of down-take and uptake headers connected by nipples, two adjacent nipples at one end of the boiler being bent away from each other, a plurality of outlet steam pipes connected to the steam space of said steam and water drum and extending downwardly therefrom, said pipes being bent at different levels into the same vertical plane and extending between said bent nipples, fittings to which said pipes are connected, and superheater tubes located between said banks of boiler tubes and connected at one end to said fittings.
  - 60 6. In a steam boiler comprising a steam space, a superheater, a plurality of saturated steam outlet pipes leading from said steam space to said superheater, branched fittings to which the respective outlet pipes are connected, each branched fitting supplying steam
  - 65

- to a plurality of sets of superheater tubes connected in series, the tubes supplied from the respective branches being connected in parallel.
- 5 7. In a steam boiler comprising a steam space, a superheater, a plurality of saturated steam outlet pipes leading from said steam space to said superheater, branched fittings to which the respective outlet pipes are connected, each branched fitting supplying steam to a plurality of sets of superheater tubes connected in series, the tubes supplied from the respective branches being connected in parallel, said superheater tubes lying in the 10 four corners of a square.
- 15 8. In a steam boiler comprising a steam space, a superheater, a plurality of saturated steam outlet pipes leading from said steam space to said superheater, branched fittings to which the respective outlet pipes are connected, each branched fitting supplying steam to a plurality of sets of superheater tubes connected in series, the tubes supplied from the respective branches being connected in parallel, and a branched fitting to the 20 respective branches of which the opposite ends of said superheater tubes are connected.
- 25 9. In a steam boiler comprising a steam space, a superheater, a plurality of saturated steam outlet pipes leading from said steam space to said superheater, branched fittings to which the respective outlet pipes are connected, each branched fitting supplying steam to a plurality of sets of superheater tubes connected in series, the tubes supplied from the respective branches being connected in parallel, the same number of tubes being connected to each branch of said fittings, and 30 all of said tubes being substantially of the same diameter.
- 35 10. In a steam boiler comprising a steam and water drum provided with a steam space, a superheater, a plurality of saturated steam outlet pipes connected to the steam space of said steam and water drum and spaced longitudinally thereof and leading to said superheater, branched fittings to which the respective outlet pipes are connected, each branched fitting supplying steam to a 40 plurality of superheater tubes connected in series, the tubes supplied from the respective branches being connected in parallel.
- 45 11. In combination with a steam boiler having a bank of inclined steam generating tubes, a baffle separating a high temperature gas pass and a low temperature gas pass, a row of saturated steam supply tubes located in the low temperature gas pass, distributor fittings secured to the tubes, groups of superheater tubes with the tubes of each group having their inlet ends joined to a fitting, the superheater tubes each having its main portion formed as a flat coil of U-shaped form, and superheated steam tubes each having 50 a distributor fitting secured thereto and located outside the high temperature gas pass, all of the superheater tubes leading from one of the first fittings having their discharge ends secured to one of the second mentioned fittings.
- 55 12. In combination, a steam boiler comprising two vertically spaced banks of inclined water tubes, vertically spaced rows of uptake and downtake headers connected to opposite ends of the tubes of each of said banks, nipples connecting the headers at each end of said banks, a steam and water drum connected to said tube banks, a superheater comprising a plurality of horizontally spaced groups of return bend tubes arranged between 60 said banks, and means for uniformly distributing steam to said superheater tube groups and effecting a high velocity flow there-through including connections passing between said water tube banks and separately and directly connecting said superheater tube groups to said steam and water drum.
